SPRING VALVE JIG

Yunus Unal, Lafayette, Ind.

Application December 12, 1947, Serial No. 791,185

3 Claims. (Cl. 29—283)

1

This invention relates to means for removing compression springs from fuel and exhaust valves of internal combustion engines and for replacing the springs on said valves.

The removal of compression springs from the valve stems of the above-enumerated valves and the replacement of such springs on the stems of said valves are extremely difficult jobs, for the reason that these springs are exceedingly strong and for the further reason that they lack a sufficient working area to engage and compress them. In other words, not only are these springs difficult to compress for the purpose of removing or replacing them with respect to the valve stem, but they are also difficult to handle and manage, so that even if a sufficiently strong force were available to compress them it could not readily be applied to them. Special tools have therefore been devised to handle such valves, but none of these tools has been found to be completely satisfactory. Some of these tools cannot exert a sufficiently strong compressive force to compress the valve spring, and others of these devices which can and do exert a sufficiently strong force for the purpose indicated, are not adapted to engage the valve spring well enough to apply their force thereto. The present device, on the other hand, is well adapted to hold the valve spring and the valve stem on which it is mounted to enable a sufficient force to be applied to the spring to compress it. It is accordingly the principal object of this invention to provide a valve holder of the character described, which enables a sufficiently strong force to be applied to the valve spring to compress the spring, either for removal from the valve stem or for replacement thereof.

All of the other devices known to applicant, which have as their object the holding of valve springs for the exertion of a compressive force thereon to remove or replace the same are designed for use in connection with a valve of a given size, and none of these devices may be used in connection with valves of different sizes. The present device, however, is adaptable for use in connection with valves of many sizes, and it is therefore a second object of this invention to provide a device of the character described, which is adaptable for use in connection with valves of different sizes.

Still another object of this invention is the provision of a device of the character described, which has no moving parts and with, therefore, cannot get out of order. All other devices of this general character known to applicant are

provided with movable parts which very frequently do get out of order.

Still another object of this invention is the provision of a device of the character described, which may be made inexpensively for sale at a relatively low selling price. Most of the devices of this general character known to applicant command relatively high prices.

A preferred embodiment of this invention is shown in the accompanying drawing in which:

Fig. 1 is a side view thereof, showing a valve stem mounted therein before the compression spring thereon is compressed to release its retaining member;

Fig. 2 is a view similar to that of Fig. 1, showing the position of the valve stem when the spring thereon is compressed and showing the spring-retaining member in released position relative thereto;

Fig. 3 is a sectional view on the line 3—3 of Fig. 1; and

Fig. 4 is a longitudinal section on the line 4—4 of Fig. 3.

It will be seen in the drawing that the device herein claimed includes a base 10 and an upright 11 mounted thereon. A tubular or cylindrical member 12 is mounted on the upright 11, and it will be noted that the longitudinal axis of said tubular member extends at a sharply acute angle with respect to the vertical. At the lower end of the tubular member 12 is a pair of diametrically opposed flanges 15. These flanges extend inwardly toward each other and their facing edges are parallel to each other.

It will be seen that the tubular member 12 is intended to accommodate a valve 16, the valve stem 17 extending downwardly through it. The valve is provided with a strong compression spring 20 which bears against a collar 21 at its upper end and against a retaining member 22 at its lower end. The retaining member rests upon an enlarged portion 23 at the lowermost end of stem 17.

In order to remove the compression spring from the valve stem, it is necessary to remove the retaining piece 22; the spring then slips over the enlarged end 23 of the valve stem.

It will be noted in Fig. 3 that the retaining member 22 is in effect a split ring having opposed flat sides 25. The retaining member 22 is also shown to possess an elevated central portion 26 which fits into the spring. It is this raised portion that prevents the retaining member from being slipped off the valve stem unless

the compression spring is in the first instance compressed out of engagement therewith.

It will be seen in Fig. 3 that the flat sides or edges of the retaining member 22 enable it to assume a position between the flanges 15 of the tubular member 12. These flanges therefore engage not the retaining ring but the spring proper. When a force is applied to the top end of the valve stem, said stem will assume the position shown in Fig. 2. The spring 20 is not shown in Fig. 2 for the reason that it has been compressed into the tubular member in which it is mounted. The flanges 15 prevent a corresponding downward movement of the spring and the retaining member 22 is thereby freed for removal, as shown in Fig. 2.

When it is desired to replace the spring on the valve stem, the spring is inserted into the tubular housing 12 until it rests upon the flanges 15. The valve stem 17 is then inserted through the spring and a force is applied thereto until it is brought into the position shown in Fig. 2. The retaining member 22 may now be slipped on the stem 17 above the enlargement 23. The force may now be removed from the valve stem and the enlargement 23 will bring the retaining member 22 into engagement with the spring 20. The spring is now locked in place.

The foregoing relates to a valve whose spring 20 is sufficiently large to engage the flanges 15 of the tubular housing 12. When a smaller valve is dealt with and its spring member is not sufficiently large to engage flanges 15, an adapter 30 must be used. This adapter is really a small version of tubular member 12. It is itself a tubular member having a pair of inwardly extending flanges 31 which correspond to the flanges 15 of tubular member 12. The outer dimensions of adapter 30 correspond to the inner dimensions of tubular member 12, and said adapter is thereby enabled to rest upon the flanges 15 when inserted into the tubular member 12. There is a pin 32 which is affixed to the side of adapter 30 and which engages a slot 33 formed in the top edge of tubular member 12. When said pin 32 is in engagement with said slot, the sides of flanges 31 are parallel to the side edges of flanges 15.

To remove a spring from a smaller valve than was above referred to, said valve is inserted into the adapter until its retaining member rests in the space between the flanges 31. The process above described is then repeated and the retaining member is thereby released.

It will be understood that the foregoing describes a preferred embodiment of this invention and that modifications may be incorporated therein within the broad spirit and scope of the invention. For example, although a single adapter is shown mounted in the tubular housing, two or more adapters may be mounted therein, one within the other. An alternative would be to introduce adapters of different dimensions into the tubular housing 12. The outer dimen-

sions of these adapters would remain constant, however, and only their inner dimensions would vary.

I claim:

1. A jig for supporting a spring valve during spring release or assembly comprising, a base adapted to rest on a work surface, an upright on said base, a tubular housing open at each end and of a length less than the length of the spring valve with which it is to be used mounted on said upright with its longitudinal axis diverging slightly downwardly from said upright, said housing having a pair of inwardly extending flanges formed at its lower end, said flanges being diametrically opposed to each other and having parallel facing side edges, said flanges adapted to support the valve assembly with the valve stem extending upwardly from said cylindrical housing.

2. A jig for supporting a spring valve during spring release or assembly, comprising a base adapted to rest on a work surface, a tubular housing open at each end and of a length less than the length of the valve with which it is to be used, supported on said base in spaced relation therefrom with its longitudinal axis at a slight angle to the vertical, said housing having a pair of opposed inwardly extending flanges formed at its lower end, a tubular member open at both ends disposed within said housing and supported therewithin on said flanges, said tubular member having a pair of facing inwardly extending flanges at its lower end, and cooperating means on said housing and said tubular member for separably interengaging the same with their flanges in register with one another.

3. The combination of claim 2 wherein said cooperating interengaging means on said housing and said tubular member comprise slots formed in the upper edge of said housing and correspondingly located pins provided on said tubular member adapted to fit within said slots.

YUNUS UNAL.
